United States Patent Office

Des. 217,737
Patented June 2, 1970

217,737

SUCTION CLEANER

Robert C. Lagerstrom, Normal, and Samuel E. Hohulin,
Bloomington, Ill., assignors to National Union Electric
Corporation, Stamford, Conn., a corporation of Dela-
ware

Filed May 27, 1969, Ser. No. 17,384

Term of patent 14 years

Int. Cl. D15—07

U.S. Cl. D49—14

FIG. 1 is a perspective view of a suction cleaner showing our new design;

FIG. 2 is a front view thereof;

FIG. 3 is a side view thereof;

FIG. 4 is a rear view thereof; and

FIG. 5 is a top plan view thereof.

The bottom of the cleaner is substantially plain and unornamented.

We claim:

The ornamental design for a suction cleaner, substantially as shown and described.
